Primary Examiner — Ricky Pham(74) *Attorney, Agent, or Firm* — Calfee, Halter & Griswold LLP(57) **CLAIM**

We claim the ornamental design for a lid, as shown and described.

DESCRIPTION

FIG. 1 is a front perspective view of a lid, with an exemplary receptacle, showing the new design;

FIG. 2 is a bottom perspective view of the lid of FIG. 1;

FIG. 3 is a left side view of the lid of FIG. 1, the right side view being essentially a mirror image thereof;

FIG. 4 is a front view of the receptacle of FIG. 1, the rear view being essentially a mirror image thereof;

FIG. 5 is a top view of the lid of FIG. 1;

FIG. 6 is a bottom view of the lid of FIG. 1; and,

FIG. 7 is an enlarged view of the designated area of FIG. 2. The broken lines shown in the drawings are for illustrative purposes only and form no part of the claimed design.
